UNITED STATES PATENT OFFICE.

CHARLES C. WHITTAKER, OF PITTSBURGH, PENNSYLVANIA, ASSIGNOR TO WESTINGHOUSE ELECTRIC & MANUFACTURING COMPANY, A CORPORATION OF PENNSYLVANIA.

BRAKING SYSTEM.

Application filed November 29, 1920. Serial No. 426,900.

To all whom it may concern:

Be it known that I, CHARLES C. WHITTAKER, a citizen of the United States, and a resident of Pittsburgh, in the county of 5 Allegheny and State of Pennsylvania, have invented a new and useful Improvement in Braking Systems, of which the following is a specification.

My invention relates to a system of motor control and it has special relation to the electrical braking of vehicle motors and the like.

One object of my invention is to provide emergency means for effecting connections 15 for electrically braking a motor upon the loss of line power.

Another object of my invention is to accomplish the above result in a manner which will be efficient in operation and reliable in 20 service.

Although the present invention will be described and is shown as a system of control for electrically propelled vehicles, it will be understood that the invention is fully 25 adapted for other uses.

Heretofore, electrically-propelled vehicles have been equipped with means for electrically braking the vehicle by some method of regeneration which is adapted for use 30 under conditions wherein the motor may be momentum-driven as, for example, when the vehicle is going down a long or steep grade.

It sometimes occurs that this regenerative 35 braking fails in its purpose because of either failure or loss of line power or other conditions. The result is that the air and mechanical brakes of the vehicle are, in that case, insufficient to maintain the vehicle 40 speed below a dangerous value, much less to safely bring the vehicle to a stop when desired.

The present invention is adapted to provide means for meeting this emergency by 45 establishing connections which will permit adequate dynamic braking of the vehicle, even though there be a total loss of line power.

My invention may be best understood by 50 reference to the accompanying drawing wherein the single figure is a diagrammatic view of so much of the circuits and apparatus embodying my invention as are necessary for a complete understanding thereof.

55 A vehicle-propelling motor 1 is shown as

having an armature 2 and a field-magnet winding 3, a variable starting resistor 4 being adapted to be connected in circuit with said armature. The motor is adapted to be energized from a source of energy through 60 a pantograph trolley 5, upon the closure of the customary knife-blade switch 6. The motor circuit includes the coil of an overload relay 7 the main contact members of the line switch 8 and the usual type of reversing switch 20, here shown in a conventional manner.

Upon the completion of the control circuit to the coil of the line switch 8, this switch will close and the motor will be energized, with the full resistor 4 in circuit. This resistor is shown as having a plurality of electromagnetic switches 9 that are adapted to shunt portions of said resistor in a well-known manner.

No detailed reference need be made to the master controller or to the main control circuits, as they are not a part of the present invention. Also, no reference will be made herein to the preferred form of regenerative 80 braking circuits, as they are fully set forth in a copending application for United States Letters Patent of A. J. Hall, P. L. Mardis, and A. McIver, Serial No. 400,159, filed July 30, 1920.

It will suffice, for present purposes, to note that the above-noted or other regenerative braking connections may be made; and the present invention is designed not only to secure all of the advantages of this system of 90 control but to add thereto an additional safety feature which will be operable should regenerative braking fail for any reason.

Therefore, the present invention contemplates the connection of a pantograph trolley 5 (in practice, there will usually be more than one), directly to the ground through a conductor 11 and the normally open main contact members of the grounding switch 12. The coil of the grounding 100 switch 12 is adapted to be energized in the following manner:

When the controller for the pantograph trolley (in practice there will usually be one at each end of the vehicle, as shown), is in 105 the "off" position, wherein the trolleys are down or disconnected from the line, a pair of control fingers 10 are adapted to be engaged by a contact segment 13 which is mounted upon the drum of the pantograph 110

controller. One of the control fingers 10 upon each controller is adapted to be energized through a connection with a positive wire extending from a battery or other source 5 of energy to the control fingers of the pantograph controllers.

The auxiliary circuit from either pantograph controller extends through a switch 14, here shown to be a snap switch, but, obviously, any other convenient type of switch 10 may be employed. This switch may be located in a housing having a glass front, so that there will be no opportunity for the accidental actuation of this switch by the 15 motorman, or anyone else.

Assuming now that regenerative braking, for previously-mentioned reasons, has failed, the motorman, upon breaking the glass, may turn the key of the snap switch 14 to close 20 this switch. At the same time, or prior thereto, both the pantograph controller and the master controller (not shown) must be returned to their "off" positions, while the reversing switch 20 must be actuated to the 25 reversed position. This condition is obvious, by reason of the fact that, until the master controller is returned to "off" position, to thereby open the line switch 8 and close the 30 interlock 19 connected thereto, the actuating-coil circuit of the switch cannot be completed.

Also, until the pantograph controller is in "off" position, the control fingers 10 will not be bridged to permit energization of the 35 circuit to the coil of the grounding switch 12.

Accordingly, with line switch 8 open, control fingers 10 bridged, and snap switch 14 closed, a circuit will be established through the pantograph controller and the snap 40 switch 14, the coil of the grounding switch 12, conductor 15, and the interlock 19, corresponding to the open position of the line switch 8, to the negative side of a battery or other source of energy. This action will 45 energize the coil of the grounding switch 12, causing it to close to thereby complete the separate grounding circuit for the disconnected trolley 5 and the knife-blade switch 6.

At the same time, the interlocking segments 50 located upon this grounding switch will complete a holding circuit for the coil 12 through conductor 16, and also a shunt circuit around the contact members of the overload relay 7 through conductors 17 and 55 18. The purpose of this shunt circuit is to render the overload relay ineffective to interfere with any temporary excessive current which may be required for the extra braking effort, particularly so if the speed of the 60 vehicle is high. Consequently, the vehicle will be uninterruptedly braked and the speed thereof will be maintained below the danger limit.

To start braking, the motorman operates 65 the master controller, whereupon the line

switch 8 will close in the usual manner, and a circuit will extend from one ground through the contact members of the closed grounding switch, the contact members of the now closed line switch, the resistor 4, 70 used now as a load, the armature 2 and the reversed series field-magnet winding 3. Thus, the closed braking circuit will be completed. Accordingly, the momentum-driven armature will generate a braking current 75 through the variable resistor 4, whereby the motorman will be enabled to control the speed of the car by movement of the master controller, in the customary manner, to gradually exclude the resistor 4 from circuit 80 and to completely stop the car, if desired.

When the vehicle is brought to rest, the snap switch 14 may be opened, which will de-energize the coil of the grounding switch 12, thereby opening this switch and also the 85 shunt circuit for the overload relay 7. A pantograph controller may then be moved to cause the trolley 5 to engage the trolley wire, as desired, whereupon the motor may be operated in the usual way, upon the manipulation of the master controller.

No detailed reference need be made to the manifest advantages of a method whereby an emergency electrical braking circuit may be established independent of any line 95 connections.

I do not wish to be restricted to the specific circuit connections or arrangements of parts herein set forth, as various modifications thereof may be effected without departing from the spirit and scope of my invention. I desire, therefore, that only such limitations shall be imposed as are indicated in the appended claims.

I claim as my invention:—

1. In a system of electrical braking for vehicles, the combination with a dynamo-electric machine adapted for regeneration and an overload relay, of means for establishing circuit connections independent of 100 said overload relay to dynamically brake said vehicle upon the failure of regeneration.

2. In a system of control, the combination with a source of energy, a dynamo-electric machine, a starting resistor and an overload relay, of means adapted to be operated upon the failure of said source to render said overload relay ineffective and to connect said motor in circuit with said resistor to electrically brake said motor.

3. In a system of control, the combination with a dynamo-electric machine having a variable resistor in circuit therewith, and a line switch adapted to interrupt the motor 115 circuit, of means adapted to be operated when said line switch is open to connect said machine in a circuit including said resistor to effect the electrical braking of the machine upon the reclosure of said line switch.

4. In a control system for electrically-propelled vehicles, the combination with a dynamo-electric machine, an overload relay, means for connecting said motor to a source 5 of energy, and means adapted to be operated when said connecting means is in "off" position to reconnect said connecting means and shunt said overload relay to electrically 10 brake said vehicle.
- 10 5. In a control system for electrically-propelled vehicles, the combination with a dynamo-electric machine and a line switch adapted to interrupt the motor circuit, of means adapted to be operated when said line 15 switch is open, to connect said machine to electrically brake said vehicle, irrespective of the speed of the vehicle, and means for maintaining such operation of the first-named means after said line switch has been 20 reclosed.
6. In a control system for an electrically-propelled vehicle, the combination with a supply circuit, a dynamo-electric machine, a current-collecting device for connecting 25 said machine to one conductor of said supply circuit, and a controller for raising and lowering said device, of means operable when said controller is in "off" or "down" position to connect said device to another 30 conductor of said supply circuit and establish other connections for operating said machine to electrically brake said vehicle.
7. In a system of control, the combination with a motor, an overload relay, a line 35 switch having an interlock connection there-
- upon, and means for connecting said motor to a source of energy, of a circuit which includes a grounding switch having interlock connections thereupon and adapted to be closed upon the disconnection of said motor-connecting means, said circuit further including the line-switch interlock, said grounding switch, when closed, completing a separate grounding circuit for said motor-connecting means and also a shunt circuit 40 for said overload relay through one of the interlocks on said grounding switch.
8. In a vehicle-braking system, the combination with a dynamo-electric machine and a current-collecting device for the vehicle, of a controller for actuating said device into and out of its operative position, a switch, and means responsive to certain concurrent operations of said switch and said controller for effecting electrical braking of said machine. 45
9. In a vehicle-braking system, the combination with a dynamo-electric machine and a current-collecting device for the vehicle, of a controller for actuating said device into and out of the operative position, a switch, and means responsive upon the open-circuiting of said controller and the closure of said switch for effecting electrical braking of said machine. 50
- In testimony whereof, I have hereunto subscribed my name this 22nd day of November, 1920.

CHARLES C. WHITTAKER.
